CLAIM

The ornamental design for a water bottle lid as shown and described.

DESCRIPTION

FIG. 1 is a right side elevation view of a water bottle lid, showing my new design, shown in use with an exemplary water bottle, further showing the spout open, the left side elevation view being a mirror image;

FIG. 2 is a right side elevation view thereof with the spout closed, the left side elevation view of which is a mirror image;

FIG. 3 is a front elevation view thereof with the spout open;

FIG. 4 is front elevation view thereof with the spout closed;

FIG. 5 is a rear elevation view thereof with the spout open;

FIG. 6 is rear elevation view thereof with the spout closed;

FIG. 7 is a top plan view thereof with the spout open;

FIG. 8 is a top plan view thereof with the spout closed;

FIG. 9 is a bottom plan view thereof, showing the exemplary water bottle removed, to show aspects of the design not visible when combined;

FIG. 10 is a rear perspective view thereof, shown in use with an exemplary water bottle, and further shown with the spout open; and,

FIG. 11 is a rear perspective view thereof with the spout closed.

The broken lines are shown for the purpose of illustrating both parts of the water bottle lid as well as environmental subject matter of an exemplary water bottle. None of the broken lines form part of the claimed design.
